US00D844874S

(12) **United States Design Patent** (10) Patent No.: **US D844,874 S**
(45) Date of Patent: ** Apr. 2, 2019

(54) LIGHTING DEVICE	2,259,106 A	10/1941	Hager
(71) Applicant: Streamlight, Inc. , Eagleville, PA (US)	2,339,356 A	1/1944	Sachs
(72) Inventors: Cleatis Eichelberger , East Norriton, PA (US); Gregory A. Roshak , Norristown, PA (US)	2,490,830 A	11/1945	Norton
(73) Assignee: Streamlight, Inc. , Eagleville, PA (US)	2,467,954 A	4/1949	Becker
(**) Term: 15 Years	2,564,612 A	8/1951	Schneider
(21) Appl. No.: 29/629,070	D166,073 S	3/1952	Dunkelberger
(22) Filed: Dec. 11, 2017	2,599,295 A	6/1952	Thomas
(51) LOC (11) Cl. 26-02	2,648,762 A	8/1953	Dunkelberger
(52) U.S. Cl. USPC D26/49	2,931,005 A	9/1954	Saurwein et al.

(57) **CLAIM**

The ornamental design for a lighting device, as shown and described.

DESCRIPTION

FIG. 1 is a front perspective view of a lighting device showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front elevation view thereof, with portions of the lighting device in an alternate configuration.

The dashed broken lines in FIGS. 1-5, 7, and 8 show unclaimed portions of the lighting device. The dashed-dotted broken lines in FIGS. 1-5, 7, and 8 show unclaimed boundaries between claimed and unclaimed subject matter. It should be understood that the dashed-dotted boundary line located at the bottom of the lighting device is located along its bottom, outermost perimeter edge. It should be further understood that the dashed-dotted boundary line located near the middle of the lighting device in FIG. 8 continues circumferentially around the lighting device, such that this boundary line forms a circle. In FIG. 8, it should be further understood that: (1) the unclaimed inwardly-sloped surface located immediately below this dashed-dotted boundary line continues uniformly around the perimeter of the lighting device; and (2) the two outermost vertical lines located immediately below this inwardly-sloped surface represent the outer edges of an unclaimed cylindrical portion, which is otherwise unornamented on its exterior surface except as shown in FIG. 8. Any portions of the lighting device that are concealed by the clip member in the Figures do not form part of the claimed design. Any portions of the top end or interior contour surfaces of the lighting device that are not shown in the Figures do not form part of the claimed design. The oblique line shading in FIG. 6 shows a translucent or transparent material. The remaining line shading in FIGS. 1-8 show surface contours, not surface ornamentation.
